PIPE WRENCH

Louis E. Peck, Greenfield, Mass., assignor to
Mechanics' Tool & Wrench Company, Green-
field Mass., a Corporation of Massachusetts

Application January 2, 1931, Serial No. 506,047
Renewed February 14, 1933

2 Claims. (Cl. 81—105)

The principal objects of this invention are to reduce the cost and increase the strength of the frame of a pipe wrench and also to substitute for the usual two springs, a single spring which 5 may be replaced without tools in case of breakage.

Other objects and advantages of the invention will appear hereinafter.

Reference is to be had to the accompanying 10 drawing in which

Fig. 1 is a side view of a pipe wrench constructed in accordance with this invention;

Fig. 2 is a side view of the frame by itself;

Fig. 3 is an end view of the frame as indicated 15 by the arrow 3 in Fig. 2, and

Fig. 4 is an edge view as indicated by the arrow 4 in Fig. 2.

The wrench is shown as provided with the usual jaws 10 and 11, the jaw 10 having a shank 20 12 provided with a screw-thread 13 and the jaw 11 having an extension 14 which constitutes the handle. A nut 15 as usual is screwed on the threads 13 for adjusting the wrench.

The frame consists of two pieces of sheet steel 25 16 and 17, each bent into a U-shaped form and one having its ends extending outwardly enough to enclose the flat sides of the other. These two parts are riveted together by a pivot stud 19 which 30 is pivoted to the handle 14 by a pivot stud 19 which also helps to hold the two parts together. The part 16 of the frame is provided with a slot 20 for receiving the nut 15. The back of the part 35 16 of the frame is straight inside so as to engage the back of the shank 12 and especially the screw-threaded portion of it. The opposite side of the portion 17 is slanted to limit the motion of the handle 14 about the stud 19 on which the handle is pivoted.

On the stud or rivet 18 inside the frame is 40 held a spring 21 which has an arcuate notch 22 in its body approximately half way between the ends. Thus the spring 21, having two ends projecting from the rivet 18, both bearing on the handle 14, will be held against the stud and will 45 not easily become displaced. It is enclosed within the part 16 of the frame and obviously is held in position against any ordinary accidents. At the same time it can be removed from the rivet and drawn out of the frame along the handle and 50 replaced by any one without the use of tools.

The manufacture of the frame of two pieces of steel formed up in a very simple manner and riveted together results in increased strength 55 over the usual malleable iron frame that has been used for so many years. Furthermore, the

cost of construction of the frame is reduced. The steel frame can be made so that it can have a more attractive appearance than the ordinary malleable iron frame and the wrench is materially improved by this construction. The fact 60 that no tools have to be used to remove the spring and that the two springs are replaced by a single one also reduces the cost of manufacture and maintenance.

Although I have illustrated and described only 65 one form of the invention I am aware of the fact that modifications can be made therein by any person skilled in the art without departing from the scope of the invention as expressed in the claims. Therefore I do not wish to be limited 70 in this respect but what I do claim is:—

1. A pipe wrench having two jaws, a handle on one jaw and a screw-threaded shank on the other, and provided with a nut on the screw-thread, a frame having a slot for the nut, said 75 frame comprising a piece of sheet steel bent into U-shaped form extending around the handle and a second piece of U-shaped sheet steel extending around the screw-threaded shank, projecting outside the first named steel piece, and riveted 80 thereto, the two parts of the frame being pivotally connected with the handle.

2. As an article of manufacture, a frame for a pipe wrench comprising a U-shaped piece of sheet steel, constituting a guide for the shank 85 of one of the jaws of the wrench, and a second U-shaped piece of sheet steel within which the handle passes, the other jaw being on the handle, one piece of sheet metal extending inside the other, and two rivets for securing the two parts 90 of the frame together, one of said rivets serving to pivot the handle to the frame.
